MULTI-ELECTRODE GASEOUS-DISCHARGE TUBE CIRCUITS

David Gurney Arnold Thomas, Deerhurst-Walton, Gloucestershire, and Edmund Harry Cooke-Yarborough, Faringdon, Berkshire, England, assignors to National Research Development Corporation, London, England

Application February 21, 1952, Serial No. 272,851

3 Claims. (Cl. 315—84.6)

This invention relates to electrical circuit arrangements using multi-cathode gaseous-discharge tubes. Circuits according to the invention have applications in electronic calculating machines.

Multi-cathode gaseous-discharge tubes, sometimes referred to as cold cathode counting tubes or polycathode glow tubes, have been described in the literature including an article "Polycathode Glow Tube for Counters," by J. J. Lamb and J. A. Brustman (Electronics, McGraw-Hill Publishing Company, November 1949, pages 92-96), an article "The Dekatron—a new cold cathode counting tube," by R. C. Bacon and J. R. Pollard (Electronic Engineering, vol. 22, No. 267, May 1950, pages 173-177) and an article "Multicathode gas-tube counters," by G. H. Hough and D. S. Ridler (Electrical Communication, vol. 27, No. 3, September 1950, pages 214-226).

In the co-pending application No. 30,715/50 there is disclosed an electrical circuit for operating a first or "receiving" multi-cathode gaseous-discharge tube according to a number stored on a second or "sending" multi-cathode gaseous-discharge tube so that the number or its complement on another number may be added to a number, including zero, stored on the first tube. Such an electrical circuit is referred to as a "transfer circuit." A multi-digit number may be stored on a cascade of multi-cathode gaseous-discharge tubes: one digit on each tube. Such an arrangement is known as a multi-digit store. The number in one multi-digit store may be transferred to another similar store by associating each tube in the one store (the "sending" store) with a corresponding tube in the other store (the "receiving" store) by means of a transfer circuit. Such an arrangement would deal with simple operations, but provision must necessarily be made for the carry-over from one digit to the next most significant digit in the receiving store. For example, in an addition operation using a decimal system, when the sum of digits of the same significance exceeds nine a carry-over must be performed to the next most significant digit.

For performing the arithmetical operation of addition of a multi-digit number in a sending store to a multi-digit number in a receiving store a carry circuit is required from each tube in the receiving store to the tube representing the next most significant digit. For the operation of subtraction by the addition of a complement it is further required that a carry circuit is provided between the tube representing the most significant digit and the tube representing the least significant digit as the least significant digit should be complemented on a number one greater than the number on which all other digits are complemented. For example, to subtract 347 from 4000, the 347 is complemented on 9999 to give 9652 from the respective transfer circuits set at the "subtract" position, the 9652 is added to the 4000 to give (1) 3652 and the most significant figure (viz. "1") is carried to the least significant figure (viz. "2") to give 3653. (i. e. 4000 less 347).

To this end, according to the invention, means are

2

provided for directing, at the completion of each transfer operation of a multi-digit number from a sending store to receiving store, a pulse from a pulse generator to each tube in the receiving store through a gate circuit opened by a carry-over condition occurring in a tube of preceding significance.

In one aspect the invention resides in an electrical circuit comprising first and second multi-cathode gaseous-discharge tubes arranged so that the position of the discharge therein represents a number, means for applying a pulse train to the first tube to step the discharge on or beyond the output electrode, means for generating an output pulse when said discharge reaches or passes said output electrode, a switch operated by said output pulse to utilise a carry pulse, generated after the termination of said pulse train, to remove the discharge on said second tube and means for restoring said switch.

Other features of the invention are disclosed in the ensuing description of preferred embodiments of the invention made with reference to the drawings wherein:

Fig. 1 shows diagrammatically the arrangements of the electrodes of one type of multi-cathode gaseous-discharge tube.

Fig. 2 shows pulse forms for operating a tube of the type shown in Fig. 1.

Fig. 3 shows a diagrammatic form of the tube as used in the circuit diagram of Fig. 4.

Fig. 4 is a simple circuit arrangement for transferring a two digit number in a sending store to a receiving store with carry facilities between the digits in the receiving store. (The references in brackets on this figure refer to the waveforms of Figure 5 existing in the connections of Fig. 4 as shown.)

Fig. 5 shows waveforms in the connections in the circuit of Fig. 4. (The numerals in brackets on this figure refer to the connections of Fig. 4 which carry the respective waveforms of Fig. 5.)

Fig. 6 is a circuit diagram of the gate circuit such as may be used as an alternative to gate circuit 37 of Fig. 4.

Fig. 7 shows the waveforms at points in the circuit of Fig. 6.

Identical reference numbers are used for identical components in the two circuits 37a of Fig. 6 and 37 of Fig. 4.

In Fig. 1, nine main discharge cathodes 1 and an output or zero cathode 2 are equally disposed round a central anode 3, and a common connecting wire 4 joins all the cathodes 1. Between adjacent main cathodes and between the zero cathode and adjacent main cathodes there are first guide electrodes 5 and second guide electrodes 6 and these have common connecting wires 7, 8 respectively. Leads 9, 10, 11, 12 are taken from the electrodes as shown. For normal operation the cathode 2 is taken through a resistance to earth or to a small bias potential and the cathodes 1 are earthed. In a typical case the electrodes 5, 6 rest at 60 volts positive and the anode is connected through a resistance of $1M\Omega$ to a 350 volt H. T. supply.

On first switching on a tube such as shown in Fig. 1 a discharge is set up between an anode and one of the cathodes 1 or 2. To move the discharge to the next cathode pulse pairs of the form shown in Fig. 2 are applied to the guide electrodes. Pulse 13, of 120 volts negative swing and 1.5 ms. duration is applied to guide electrodes 5 thus causing the discharge to move from the cathode on which it initially rested to the adjacent electrode 5. At the end of pulse 13, a pulse 14, similar to pulse 13, is applied to guide electrodes 6 to move the discharge on to the adjacent electrode 6 which has become more negative than any adjacent electrode or cathode. At the end of pulse 14 the discharge moves to the cathode 1 adjacent to the electrode 6, and thus the dis-

charge has completed one step between adjacent cathodes. It is not necessary for the pair of pulses 13 and 14 to overlap, but it is important for any time interval between the end of pulse 13 and the start of pulse 14 to be less than the deionisation time of the tube.

In Fig. 3 a multi-cathode tube is represented diagrammatically. Electrode 16 is the anode, electrode 17 is the output or zero cathode having an output terminal 18 and a resistance 19 to earth. The main cathodes connected to earth are identified by electrode 20; the first 10 guide cathodes by electrode 21 and the second guide cathodes by electrode 22.

In the operation of a tube such as disclosed with reference to Fig. 1 a number "n" may be passed for storage by applying "n" pairs of pulses such as the pair of pulses 13, 14 of Fig. 2 so that the discharge advances "n" steps.

In Fig. 4 the sending store consists of two multi-cathode tubes 31, 32; the discharge in tube 31 representing the most significant digit and the discharge in tube 32 representing the least significant digit of a two digit number. The receiving store consists of two multi-cathode tubes 33, 34; tube 35 for the most significant digit and tube 34 for the least significant digit. Transfer circuits 35, 36 of the type disclosed in the co-pending application 30,715/50 couple tube 31 with tube 33 and tube 32 with tube 34 respectively. A gate circuit 37 is provided between tube 34 and tube 33 and is arranged to be opened by a carry-over condition occurring at the output electrode 39 of tube 34 which is the tube of preceding significance relative to tube 33. In a similar manner a gate circuit 38 is provided between tube 33 and tube 34 and is arranged to be opened by a carry-over condition occurring at the output electrode 67 of tube 34; such as would be met in the arithmetical operation of subtraction as previously described; tube 33 being the tube of preceding significance relative to tube 34.

Gate circuits 37 and 38 are similar and the detail of these circuits is described with reference to circuit 37. The circuit consists of a cold cathode gaseous discharge trigger tube 40, triggered by the output pulse from the output electrode 39 of tube 34, and a double triode tube 41 which normally conducts by way of anode 42 but is switched to conduct via anode 43 by a pulse generated at the cathode 44 of the tube 40 when it is triggered. The anode 42 has a connection 45 back to a pulse generator 46 for the transmission of a "finish" signal to that generator. The anode 43 has a connection 47 including a rectifier 50, to the second guide electrode 48 of the tube 33 and a connection 49 including a rectifier 51 to the anode of tube 40. The cathode 52 of the double-triode tube has a connection 53 to the pulse generator 46. A pulse train applied to cathode 52 when the tube 41 is conducting via anode 43 allows the first pulse of the train to pass via that anode but also depresses the voltage on the anode of the trigger tube 40 so that it is extinguished to restore the conducting path of tube 41 via anode 42, thus allowing only the first pulse of that train (the carry pulse) to pass to the tube 33. The pulse generator 46 has a connection 54 to the first guide electrodes 55, 56 of tubes 31 and 32 respectively for a pulse train of the form shown in Fig. 5(a) and a connection 57 to the second guide electrodes 58, 59 for a pulse train of the form shown in Fig. 5(b). A connection 60 feeds a pulse train of the form shown in Fig. 5(c) to the first guide electrodes 61, 62 of tubes 33 and 34 respectively. Other connections include connections 63 and 64 from transfer circuits 35, 36 to the second guide electrodes 48, 65 of tubes 33 and 34 and connections 47a, 45a and 53a having functions in relation to circuit 38 similar to that of connections 47, 45 and 53 in relation to circuit 37. Connection 66 carries pulses to the transfer circuits 35, 36.

The operation of the circuit of Fig. 4 will now be shown in conjunction with the waveform of Fig. 5, by consideration of the simple case of adding a number "56" stored in tubes 31 and 32 (the sending store) to a

number "39" stored in tubes 33 and 34 (the receiving store).

The pulse generator feeds two trains of ten pulses (Figs. 5(a) and 5(b)) by way of connections 54 and 57 to circulate the discharge in tubes 31 and 32 one complete revolution. This results in five pulses being fed to electrode 48 of tube 33 (Fig. 5(d)) and six pulses being fed to electrode 65 of tube 34 (Fig. 5(e)) from the respective transfer circuits set at the "add" position. A train of nine pulses in connection 60 (Fig. 5(c)) couple with the pulses at electrodes 48 and 65 to move the discharge in tube 33 by five steps and the discharge in tube 34 by six steps. That is, the discharge in tube 33 is moved from its third to its eighth discharge electrode and the discharge in tube 34 is moved from its ninth to its fifth discharge electrode passing its output electrode on the way to set up an output pulse to trigger discharge tube 40. The pulse train in connection 60 is extended as shown by the dotted portion of Fig. 5(c). The pulse train normally fed to connection 66 is extended (Fig. 5(f)) and switched to feed instead along connection 53. The first pulse of this extended train feed via anode 43 (as tube 41 has been switched by the triggering of tube 40), and couples with a pulse in the extended pulse train in connection 60 to move the discharge in tube 33 by one step, that is on to its ninth discharge electrode. In this manner a number, 95 (the sum of 56 and 39), is stored in the sending store.

Referring to Fig. 6 and Fig. 4 of the drawing the gate circuit 37a may be provided in lieu of circuit 37 between tube 34 and tube 33, and a similar circuit may be provided, in lieu of circuit 38, between tube 33 and 34.

As stated above the tube 41 normally conducts by way of anode 42 but it is switched to conduct via anode 43 by a potential generated at the cathode 44 (Fig. 7c) of the tube 40 when it is triggered by the output pulse from electrode 39 (Fig. 7b). Tube 40 continues to conduct (Fig. 7c) until the anode potential is suppressed by a pulse (Fig. 7f) coincident with the pulses fed to cathode 52 (Fig. 7e) of valve 41. The tube 41 is held conducting by way of anode 43 although tube 40 has ceased to conduct by a pulse train fed to connection 68 (Fig. 5d) from the pulse generator 46. This arrangement allows the passage of one pulse only via anode 43 (Fig. 5g) to second guide electrode 48 to perform the "carry" operation.

The waveforms of Fig. 7 represent the potential in the various connections as follows:

Fig. 7a is the waveform shown in Fig. 5b and is shown for reference purposes.

Fig. 7b is an output pulse from electrode 39 occurring at the point shown in the waveform of Fig. 7a.

Fig. 7c is the waveform at cathode 44 of tube 40.

Fig. 7d is the waveform applied at connection 68.

Fig. 7e is the waveform applied at cathode 52 of tube 41.

Fig. 7f is the waveform applied to the anode of tube 40.

Fig. 7g is the pulse in connection 47 to perform the "carry" operation.

We claim:

1. A computing machine comprising at least two multi cathode gaseous discharge tubes constituting a multi digit sending store; at least two further multi cathode gaseous discharge tubes constituting a multi digit receiving store, a transfer circuit connected between each pair of tubes of equal significance in the sending and receiving stores, a pulse generator for supplying trains of pulses to said sending store and to said receiving store under the control of said transfer circuit, and a carry circuit between tubes in the receiving store, said carry circuit comprising a gate circuit operated by an output condition in a tube of the receiving store to pass a carry pulse from said generator to another tube in said receiving store.

2. A computing machine as claimed in claim 1 wherein the gate circuit comprises a trigger cold cathode gaseous discharge tube and grid controlled electronic valve, a

connection from the cathode of the trigger tube to the grid of the valve, a connection for feeding pulses to the cathode of the valve from said generator and a rectifier coupling the anodes of the trigger tube and the valve so that the change in anode potential of the valve when a pulse passes through the valve depresses the anode potential of the trigger tube.

3. A computing machine as claimed in claim 1 wherein the gate circuit comprises a trigger cold cathode gaseous discharge tube and two grid controlled electronic valves having a common cathode connection and arranged so that normally one valve conducts and the other is cut off, a connection from the trigger tube to the grid of the normally non-conducting valve to feed a potential to that grid when the trigger tube fires to switch the conducting path from the normally conducting valve to the other

5 valve, means for connecting a pulse train from said generator to the common cathode connection, means for quenching the discharge in the trigger tube when one pulse has passed through the normally non-conducting valve and a connection from the anode of the normally conducting valve to said generator.
